UNITED STATES PATENT OFFICE.

DANIEL M. READ AND HENRY C. DIEFENBACH, OF NEW YORK, N. Y.; SAID
DIEFENBACH ASSIGNOR TO SAID READ.

DESIGN FOR LOCKS FOR POCKET-BOOKS.

Specification forming part of Design No. 7,918, dated December 8, 1874; application filed October 3, 1874.
[Term of Patent 14 years.]

To all whom it may concern:

Be it known that we, DANIEL M. READ and HENRY C. DIEFENBACH, of the city, county, and State of New York, have invented a Design for Locks for Pocket-Books, of which the following is a specification:

The figure is a front view of a lock, showing our improved design.

Similar letters of reference indicate corresponding parts.

A represents the case of the lock, the upper part of which is made narrower than the lower part. The edge of the wider lower part of the case A is slightly concaved. The edge of the narrower part is slightly convexed, and the side edges are scalloped, as shown. Around the entire edge of the case A runs a row of fine dots or beading. B is the knob, the ends of which are rounded off, and which taper gradually from the said ends toward its center. A row of fine dots runs around the longitudinal slot in the middle part of the case A, and through said slot are seen the teeth C, which adds greatly to the appearance of the lock. Through the said slot is also seen the back

plate D, giving to the slot the appearance of a deep recess, and thus producing a pleasing effect.

Having thus described our invention, we claim as new and desire to secure by Letters Patent—

1. The design for a lock-case, in which the lower part is made wider than the upper part, the lower edge is slightly concaved, the upper edge is convexed, the side edges are scalloped, a row of small dots or beading runs around the entire edge, and another row of small dots or beading runs around the slot, substantially as herein shown and described.

2. The design for the knob of the lock-case, in which the ends are rounded off, and which tapers gradually from said ends toward the center, substantially as herein shown and described.

DANIEL M. READ.

HENRY CH. DIEFENBACH.
